BENJAMIN NOTT, OF ALBANY, NEW YORK.

Letters Patent No. 83,877, dated November 10, 1868.

ILLUMINATOR FOR STOVES, GRATES, &c.

The Schedule referred to in these Letters Patent and making part of the same.

Be it known that I, BENJAMIN NOTT, of Albany, in the county of Albany, and State of New York, have invented a new and useful Improvement in Illuminators or Transparents for Stoves, Grates, Ranges, Furnaces, &c.; and I do hereby declare that the following is a full, clear, and exact description thereof, reference being had to the accompanying drawings, which make part of this specification, and in which—

Figure 1 represents a view in perspective of my improved illuminator;

Figure 2, a horizontal section of the same;

Figure 3, a view in elevation, and on a smaller scale, of the slide D; and

Figure 4, a view in perspective of my improved illuminator as placed in position upon a stove.

The object of my invention is to produce an illuminator or translucent to be attached to the door of a stove, grate, range, or heater, for the purpose of diffusing the light of the fire through the room, and which shall be so arranged as to obviate risk of having the glass broken by sudden changes of temperature, or soiled and blackened by smoke in kindling the fire; to which ends my improvement consists in hinging to the door of a stove or heater, or to the stove itself, so as to be used as a door, a metallic frame or case, closed at the front by a glass plate, behind which are arranged glass cylinders, and open to the fire at its rear, which can be closed at pleasure by doors or dampers, either perforated or tight.

In the accompanying drawings, which show a convenient arrangement of parts for carrying out the objects of my invention, A represents the metallic frame or case, which, in this case, is hinged to the stove-door B, the latter being provided with an opening, H, of similar shape and size to the rear side of the case A, and before which the case is hung. The case may be attached directly to the stove, so as to act as a door, if desired. A vertical glass plate or slide, E, is placed in the case A, a short distance from the front, which is open. This plate prevents heat or smoke escaping into the room, but of course allows the light to pass, and, being very near the front of the case, is not exposed to excessive heat. Hollow cylinders of glass, F, are arranged side by side, and in a vertical position, in rear of the plate E. These cylinders serve to reflect the light, and diffuse it with a pleasant effect on the room. Currents of air pass through the cylinders F by means of holes in the bottom of the case beneath them, and perforations in the hinged top, G, of the case.

Communication may be shut off from the case to the stove, when desired, either by the slide D or doors C C'. The door C is shown as perforated, and is operated by the handle a, the door C' being plain, and operated by a similar handle. By means of the slide or doors, the cylinders F and plate E can be protected from excessive heat when necessary, and also from the smoke which is evolved in kindling a fire. The cracked and discolored appearance which the mica ordinarily used in stove-doors presents, disfigures them, and materially impairs translucent effect, and is due to the lack of protection from the heat and smoke.

My invention is applicable to any form of stove or heater, and can be attached either to the door, as hereinbefore described, or to the stove itself in the manner of a door, and the cylinders and slides can be readily removed and replaced, when desired, for purposes of cleaning or repair. Colored glass can be used, if desired.

Having thus fully described my invention, What I claim therein as new, and desire to secure by Letters Patent, is—

1. The within-described illuminator, hinged to a stove or other heater in the manner and answering the purpose of a door, as set forth.

2. The hollow glass cylinders F, having currents of air circulating through them, substantially as and for the purpose as set forth.

3. Using glass cylinders to transmit the light from a stove or heater, when protected by adjustable doors or dampers in rear thereof, as set forth.

4. The cylinders F, in combination with the plates D and E, or either of them, substantially as and for the purpose set forth.

5. The cylinders F, in combination with the doors C and C', or either of them, substantially as set forth.

6. The combination of the cylinders F, plates D and E, or either of them, with the doors C and C', or either of them, substantially as set forth.

7. The combination of the cylinders F, plates D and E, or either of them, doors C and C', or either of them, with a stove, or door of a stove, substantially as set forth.

BENJAMIN NOTT.
